CLAIM

The ornamental design for a support for furniture, as shown
and described.

DESCRIPTION

FIG. 1 is a perspective view taken from the top, front and left
side of a support for furniture in the form of a table leg
embodying my new design;

FIG. 2 is a top plan view thereof;

FIG. 3 is a front elevational view thereof, the rear elevational
view being the mirror image thereof;

FIG. 4 is a right side elevational view thereof, the left side
elevational view being the mirror image thereof;

FIG. 5 is a perspective view taken from the top, front and
right side of a second embodiment;

FIG. 6 is a top plan view of the FIG. 5 embodiment;

FIG. 7 is a front elevational view of the FIG. 5 embodiment,
the rear elevational view being the mirror image thereof;

FIG. 8 is a right side elevational view of the FIG. 5
embodiment, the left side elevational view being the mirror
image thereof;

FIG. 9 is a top plan view of a third embodiment;

FIG. 10 is a front elevational view of the FIG. 9 embodiment,
the rear elevational view being the mirror image
thereof; and,

FIG. 11 is a right side elevational view of the FIG. 9
embodiment, the left side elevational view being the mirror
image thereof.

The fragmentary broken line representations of additional
linked support elements in FIGS. 4, 8, and 11 are for the
purpose of illustration only and form no part of the claimed
design.
